Primary Examiner — Kevin Rudzinski*Assistant Examiner* — Sean D Lough(74) *Attorney, Agent, or Firm* — J. Douglas Wells(57) **CLAIM**

The ornamental design for a horticulture grow light fixture, as shown and described.

DESCRIPTION

FIG. 1 is a perspective view of a horticulture grow light fixture, as viewed from below, showing my new design; and, FIG. 2 is a bottom plan view of the light fixture shown in FIG. 1.

The broken-line disclosure shown in the views is understood to represent portions of the article in which the claimed design is embodied, but which form no part of the claimed design.
